HYDRAULIC MOTOR

Elek K. Benedek, Bucyrus, Ohio

Application May 10, 1934, Serial No. 724,933

7 Claims. (Cl. 121—61)

This invention relates to improvements in hydraulic motors of the radial piston type and its principal object is to provide a highly efficient, hydrostatically and mechanically balanced, compact motor unit having starting and operating torque capabilities comparable to the more efficient types of mechanical and electric transmissions.

A further object is to provide a hydraulic rotary motor of the radial piston type wherein the hydrostatic pressures are balanced about the center of relative rotation of the main driving member of the motor.

A further object is to provide supporting bearings for the piston carrying rotor so arranged with reference to the cooperating parts that all the relatively rotating working parts are maintained in accurate alignment and in undistorted condition during varying conditions of power input and output.

Still another object is to provide a hydraulic motor of the radial piston type wherein viscosity losses and flow restriction losses, particularly at the valves, are reduced substantially to a minimum.

Still another object is to provide in a hydraulic motor of the type referred to a more compact valve arrangement for feeding operating fluid medium to the piston cylinders and discharging said medium therefrom.

Still another object is to provide, in a hydraulic motor of the type referred to, a compact and balanced arrangement of pistons, operating cams, bearings and driving shaft for the piston carrying rotor thereby reducing as much as possible the tendency for the piston carrying rotor to tend to become disaligned with the relatively rotating parts due to unbalanced mechanical stresses.

Another object is to provide a hydraulic motor of the radial piston type wherein the mass of the rotor is always in dynamic balance about the axis of rotation of the rotor.

Other objects include the provision of various inter-related methods of supporting the rotary and reciprocating parts of a hydraulic motor of the radial piston type whereby hydrostatic and mechanical losses are minimized and the forces imposed on the main rotating parts are most effectively utilized from the standpoint of torque delivery.

Motors of the radial piston type of the present conventional designs are very inefficient and lack particularly good starting torque characteristics. This is an important deficiency inasmuch as these motors must compete commercially with electro

and mechanical transmissions wherein the power is more directly applied. It is an inherent characteristic in hydraulic motors that these motors must operate in conjunction with hydraulic pumps or generators of some sort and, since power has already been transformed once in such pumps or generators, further loss must be minimized as much as possible in the motor if the total efficiency of the generator-motor unit is to be maintained high enough to compete with transmissions of the other types mentioned.

It is particularly important that when the pressure power of the generator is weak the motor used in conjunction therewith must have an efficiency comparable to ordinary geared transmissions or the hydraulic motor is incompetent from the standpoint of commercial utility.

In order to accomplish the above objects and approach as nearly as possible the ideal characteristics mentioned above, I provide first, an unusually rigid general structure, that is rigid enough to withstand the highest applied pressures and the greatest torque delivery and at the same time I reduce the frictional losses as much as possible both by the provision of adequate rolling bearings and by the distribution of the load on these bearings such that a balanced condition is maintained at all times. One outstanding characteristic of the motor is the provision of a specially fitted drive shaft for the main rotor, which shaft will be certain to remain in alignment with the rotor under all conditions of increased torque at decreased motor speed as well as less torque at very high speeds without danger of collapse, deflection or distortion, of the parts and excessive wear on the bearings.

A further important characteristic is the compact and balanced arrangement of multiple valves so arranged that at all times the film spread of the hydraulic operating medium is confined within reasonable limits and uniformly distributed about the working axis of the motor, thus reducing any tendency for the working fluid to distort either the valve carrying member or the rotor or the driveshaft operating in conjunction therewith. I have further provided a definite relationship between the valves and valve ports and the operating cams for the pistons and also the mountings for the pistons by which during all operating conditions both hydrostatic pressures and mechanical forces are in balance.

Other objects and features of the invention will become apparent from the following description relating to the accompanying drawings showing

the preferred forms and arrangement of the parts.

In the drawings:

Fig. 1 is a longitudinal central sectional view of one form of motor;

Fig. 2 is a transverse sectional view taken substantially along the line 2—2 on Fig. 1, portions of a driving flange, however, being removed for clearness of illustration of the reactance cams;

Fig. 3 is a transverse sectional view taken along the line 3—3 of Fig. 1;

Fig. 4 shows in cross-section (same plane as Fig. 2) the port arrangement of a pintle, which would operate in combination with my special cam profile, shown in Fig. 8; and

Figs. 5 to 10 show diagrammatically the basic curves of my multi-sectional cams and the dead center positions of radial pistons relative to the cams;

Fig. 11 is a left hand end elevation of the cylinder barrel removed from the associated parts;

Fig. 12 is a fragmentary sectional view taken on a plane indicated by the line 12—12 in Fig. 11;

Fig. 13 is a fragmentary plan view of the barrel with the plungers removed as viewed from the plane 13—13 in Fig. 11;

Figs. 14 and 15 are sectional views taken on planes indicated by the lines 14—14 and 15—15 respectively, in Fig. 1;

Figs. 16 and 17 are front and end elevations respectively of a plunger and cooperating rollers;

Fig. 18 is a sectional view of a plunger with the thrust means and bearings removed and is taken on a plane indicated by the line 18—18 in Fig. 16.

In the illustrated embodiment of Figs. 1 to 3, 1 indicates the driving shaft which is adapted, by the use of suitable couplings or connections, to turn the spindle of an automatic machine tool or the driving shaft of an automobile or Diesel driven locomotive, for example. The shaft has an enlarged head 3 which is tapered and accurately fitted to a corresponding tapered bore of the piston carrying rotor 5 supported in the motor casing as will be hereinafter described. The tapered head 3 is secured against rotation in the tapered bore by means of a feather key 4 and the tapered surfaces are drawn into stressed engagement with each other by a suitable nut 6 threaded onto the shaft as at 2. The tapered connection of the shaft to the rotor insures the proper rigid relationship between the shaft and rotor and insures the absolute axial alignment of the shaft and rotor during all working conditions, thereby minimizing any tendency of the shaft to become loose in the rotor and wobble; it being manifest that any wobble, however slight, would, when once set up, render the entire unit useless in a short time.

The drive shaft is entirely supported by the rotor 5. The rotor has hub portions 7 and 7a at its ends through the medium of which and of interposed bearings 17 it is supported by a very rigid casing comprising generally cup-shaped end plates 19 and 20 having hub portions at 21 and 22 respectively. The end plates 19 and 20 are rigidly connected together by an annular casing member 34, said casing parts being accurately aligned by suitable shoulders and bolted together in the conventional fashion (bolts not shown). The hub 21 of the casing part 19 is relatively elongated and rigidly carries a stationary pintle 23 of relatively large diameter at its region of support and inwardly therefrom toward the interior of the casing, the pintle projecting into the rotor 75 at one end and having a reduced diameter valve

portion at 24 in working contact with a complementary valve portion of the central bore 5' in the rotor. Preferably the adjacent surfaces of the reduced diameter valve portion of the pintle and the valve portion of said bore of the rotor are slightly tapered (taper not shown) and are smooth fitted by lapping. These surfaces operate in very close relation to each other at all times, sufficient operating clearance, however, being assured by slight axial movement of the rotor on its bearings 17 with reference to the pintle, this movement being proportionate to the operating load on the motor, providing slightly greater clearance when the load is excessive than during lower load output. Considerable clearance is provided as at 7" between the larger diameter portion of the pintle and the surrounding portion of the rotor as well as at 1' between the radial shoulder which connects the large and small diameter portions of the pintle and the adjacent surface of the rotor. A similar arrangement is disclosed and claimed in my earlier filed copending application, Serial No. 716,451, filed March 20, 1934.

The bearings for the rotor comprise inner bearing rings 16 and outer bearing rings 18, the inner rings being tightly fitted, as by press fit onto the rotor hubs 7 and 7a and shouldered thereagainst and the outer bearing rings being accurately seated in suitable shouldered cylindrical surfaces in the casing parts 19 and 20. The anti-friction bearing elements may comprise suitable balls 17. The bearings are designed both to resist radial load as well as axial thrust, wherefor the balls are deeply seated in the bearing races and the operating clearance between the balls and race channels is very slight. It will be noted that the balls 17 are in radial alignment respectively with the relatively larger portion of the pintle which projects into the clearance spaces 7' and 7" of the rotor and with the tapered connection between the drive shaft and the rotor. It will be further noted that the main bearing diameters are approximately equal to the overall axial length of the rotor portion embraced by the bearings, this relationship being important to minimize deflection of the axial midportion of the rotor surrounding the reduced valve portion 24 of the pintle wherein the valve ports are located and to reduce the peripheral speed of the bearings at average speeds of operation of the motor.

Another highly important relationship, is between the axial spacing of the bearings and the maximum axial film spread of the working fluid at the pintle valve portion, the actual axial extent of working contact between the valve portion 24 of the pintle and the coaxing surface of the rotor being determined by the maximum film spread of the working fluid at maximum pressure of the fluid in driving the motor. It will be noted that the bearings 17 are spaced a distance equal to about twice the length of the cooperating valve portion of the pintle and rotor, in other words, twice the maximum axial film spread at maximum fluid pressure.

In the barrel 5, in the radial plane of the central portion of the reduced valve portion 24 of the pintle are a suitable number of radial cylindrical bores 10, in which reciprocable pistons 11 are carried. The pistons may, for greater economy and rigidity, be made each in one piece and at their outer ends, each has a transverse bore 11a, as better illustrated in Fig. 18, carrying relatively small needle roller bearings 75

13 and a hardened cross pin 14 embraced and supported by the bearings in true parallelism with the axis of rotation. The oppositely projecting ends of the cross pins 14 carry suitable hardened rollers 15 (pressed on the cross pins for example) for contact with the surfaces of the operating cams which may be formed directly on axially spaced portions 33 and 33' of the casing member 34 in which event the member 34 is of properly selected and treated steel suitable for use in heavy duty cams. The cam contours, will be hereinafter more fully discussed, but comprise a plurality of separate cam profile sections subject to considerable modification, but each having both inwardly and outwardly directed surfaces operating as reaction members under the impelling force of the working fluid on the pistons to turn the rotor, and also to effect the discharge of the used fluid medium from the motor.

As shown in Fig. 3, the fluid medium is preferably fed as through a main inlet 27 in the hub 21 of the plate 19 into a manifold or distribution groove 25 between the pintle and said hub. From thence the fluid passes through radial openings 30 in the pintle aligned with the distribution groove and into longitudinally extending bores 29 circumferentially spaced within the body of the pintle and extending from the plane of the radial holes 30 to the middle of the reduced diameter portion of the pintle. Radial inlet ports 30' are formed in the reduced portion of the pintle for communication with the piston cylinders through respective openings 9 in the inner wall 35 of the rotor. The working fluid is thus fed to the cylinders at certain positions of these cylinders about the axis of the pintle during rotation of the barrel 5. The position and number of the radial ports 30' is determined by the number of cam profile sections or lobes of the cams, that is to say, if there are four profile sections as illustrated in Fig. 2 in equally spaced circumferential relationship then there are four inlet ports 30' identically spaced about the reduced end of the pintle. This distribution of inlet ports about the axis of the pintle results in that the positive hydrostatic forces of the fluid medium during film spread at the valve are always balanced on radially opposite zones of the coating surfaces 50 of the pintle and rotor and there is, at no time, any hydrostatic force applied in such manner as to tend to throw the rotor toward one or the other side of its axis as in prior motors of the radial piston type or to deflect the pintle.

In prior motors of the hydrostatically balanced type, having not more than two complete cam profile sections and therefore only two effective inlet and two effective exhaust ports at the valve, the film spread about the entire circumference of the valve cannot, without such clearance between the working surfaces as will too greatly reduce efficiency, be such as to fully lubricate the surfaces and maintain the pressures in hydrostatic balance on diametrically opposite surfaces of the valve at the same time. My arrangement of valve ports, close together, accomplishes this, since at all times minimized positive pressure fluid film spread will be present as much as necessary for proper lubrication notwithstanding unusually close working clearance between the pintle valve portion 24 and the wall of the rotor bore 5'.

It should be further noted that by the arrangement of ports close together, the circumferential film spread during operation of the

motor is minimized between the working surfaces of the rotor and pintle (valve portion 24) and this is one of the outstanding advantages of my arrangement of cam profile sections and valve ports, wherein the valve ports are sufficiently close to one another to effect instantaneous fluid film spread on the entire periphery of the valve portion 24 of the pintle to immediately effect hydrostatic balance and thus prevent the locking effect of unbalanced hydrostatic pressure which would expand with various spread on the surface according to the smoothness or roughness of the adjacent hydraulically fitted surfaces at the bottom motor speed.

The working fluid after operating to move the pistons radially outwardly is thereafter discharged through the cylinder ports 9 into short valve ports 31 and 32, which communicate directly with an enlarged central bore 28 in the pintle, which bore 28 has one end terminating in radial alignment with the said short exhaust ports and the other end open as at 26, as illustrated in Figs. 2 and 1 respectively, for connection with suitable piping to lead the fluid medium from the motor. This valve and duct arrangement provides for the free discharge of the operating fluid medium from the motor cylinders without imposing any appreciable dead load on the motor during the discharge operation. It is manifest that the larger and more direct the discharge openings and ducts for exhaust operating fluid are, the less drag or dead load will be imposed on the motor in ejecting the fluid. The present solution practically minimizes both skin friction and viscous friction of the discharging fluid.

In order that the wear on the pistons will be minimized I provide, on the rotor 5, a radial driving flange 8 which extends outwardly from the rotor 5 in the plane of the cylinders, and the cylinder bores are extended outwardly through said flange, and form guideways 8a therein and provide slots 8' for the crosspins 14, as better illustrated in Figs. 11 to 15 inclusive. It will be seen that by this arrangement the pistons are fully supported in a uniform manner throughout their entire length both fore and aft in the direction of rotation of the rotors and there can be no possibility of the peripheral forces imposed on the cross pins by the cams enlarging or distorting the cylinder bores unnecessarily or wearing the adjacent surfaces of the pistons or in any manner deflecting the pistons transversely of their axes.

Each cam is divided into pressure and exhaust portions, the circumferential extent of a given cam portion which acts on a piston to cause it to complete one pressure and one exhaust stroke, being herein referred to as a cam profile section. Otherwise stated each cam comprises a connected series of convex and concave profiles.

Referring now to the cam contours, the cam profile sections, illustrated in Fig. 2, each comprise an inwardly directed surface circumferentially coextensive with the angular indication A and an outwardly directed, preferably identical, surface angularly coextensive with the arc indication B. The term "inwardly" is with reference to the direction of rotation of the rotor and the corresponding action of the piston in riding over this surface. In other words, since fluid admitted at the ports 30' is acting to move the adjacent pistons outwardly the surface defined by the arc A e. g. may be considered an outwardly directed surface, whereas since the ports 31 are, in the illustrated condition, acting to discharge

fluid from the adjacent piston cylinders the cam surface measured by the arc B e. g. may be said to be an inwardly directed surface. I contemplate considerable modification of these cam surfaces, the essential differences, however, from prior practice being the provision of a greater number of complete profile sections including both inwardly and outwardly directed surfaces than two.

10 The basic contours of the inwardly and outwardly directed cam surfaces are illustrated in Figs. 5 to 10, wherein the power applying and fluid discharge portions of the individual cam profile sections are shown as meeting abruptly; however, it is understood that the meeting portions of the curves would be rounded more or less, depending upon the starting and running torque and speed requirements of the motor. In Fig. 5, 5 represents the rotor and the radial lines of 15 symmetry 39—42 denote the dead center positions of the pistons on the cams, as well as the separation lines of the cam sections.

15 Figs. 6 and 8 illustrate that an uneven number of profile sections may be provided with, of course, the proper number of inlet and exhaust ports in the valve which number is twice the number of cam profile sections. Fig. 6 shows a quinquefoil arrangement of cams and Fig. 8 shows a trefoil arrangement. The radial lines of 20 symmetry denoting the dead center positions of the pistons on the cams are indicated from 43 to 25 52 on Fig. 6 and the cams of Fig. 8 are similarly divided. Each of the cams has twice as many dead center positions as its name calls for; a trefoil six, a quatrafoil eight etc.

30 The cam arrangement according to Fig. 7 is characteristically different from the previously described cam forms in that there is a very short, relatively convex, cam surface only. The dead center positions on the cams are partially indicated by radial lines 53 to 58. This form of cam is particularly adapted to motors designed for low speed and great torque. A motor with the piston arrangement of Fig. 2 and the cam arrangement of Fig. 7 would operate with very little vibration since the starting torque would be very gradual while the piston is moved from the line 35 55 counterclockwise toward the line 54, it being obvious that with the cross pin rollers at the position 55, the force component tending to drive the rotor in the direction of the arrow would be very small but increasing proportionately with the rotational angle as the rollers approach the position 54. Such a motor would approach the 40 torque characteristics of a series electro-motor with the starting torque increasing directly with the load. In like manner the starting torque characteristics of the motor with any of the other cam arrangements may be varied by the 45 modification of the cam contours. For example, the cam arrangement of Fig. 8 would approach more nearly a triangle with the rounded apices and the arrangement of Fig. 6 would approach more nearly a pentagon with rounded apices.

50 In any case the driving torque will be exerted by the tangential component of each radial piston load. Since the pistons are all radial the piston load will be radial and this radial load will have a projected component into and on the geometrical tangent of the cam curve in that particular point of the cam path in which the center line of the piston intersects the cam profile curve. The geometrical tangents of the cam curves will be perpendicular to the cam curve radii which 55 pass through the center of curvature of each con-

cave and convex portion of the cam. Thus in analyzing the torque characteristics of the motor with the different cams the actual tangential force and its torque may be graphically determined and illustrated. The torque naturally will 5 be the product of the tangential force and the torque radius (instantaneous).

It has been demonstrated that with the arrangement of four cam profile sections and six pistons, as shown in Fig. 2, whenever the pistons 10 are moving outwardly under the positive force of the fluid medium, the same mechanical force is applied to the pistons on opposite sides of the center of rotation of the rotor and that the hydrostatic forces which are set up by the film spread 15 at the valve are balanced on opposite sides of the same center of rotation. These conditions obtain from the inward dead center positions of the pistons until the pistons are in their outermost dead center positions, (not shown) and thereafter any mechanical forces imposed by the action of the relatively inwardly directed portions of the cams on the pistons in the fluid ejecting operation are likewise balanced about the axis of rotation. These forces are, of course, rendered negligible by the free passages provided for discharge 20 of the operating fluid but regardless of such free passages the forces, upon the discharging operation of the pistons, are balanced. The ratio of the number of cam profile sections to the number 25 of pistons in the Fig. 2 arrangement is 2:3. The same ratio could be used for the cams of Figs. 5 and 7. This identical ratio cannot be maintained for the cam arrangement of Fig. 8 e. g. but nevertheless by providing 12 pistons, the operative 30 characteristics of the motor and balanced condition of forces will be the same as heretofore described. In the Fig. 6 arrangement of cams one manner in which results comparable to those obtained by the Fig. 2 arrangement could be obtained would be by providing 20 pistons, in which event the above described balance and starting 35 characteristics would be fulfilled.

It may be found impractical to provide so great a number of pistons, as required for Figs. 6 or 8 40 e. g., in a single series, wherefore I may divide the required numbers into appropriate groups and arrange the groups in axially offset relationship with reference to the pintle. For instance for the three section cam of Fig. 8 I may provide two 45 groups of 6 pistons each and with a valve port arrangement according to Fig. 4 for each group of pistons (see also dotted line indication of valve port arrangement on Fig. 8). In Fig. 8 the full radial lines 57, 58, 59, 60, 61 and 62 represent one 50 group of pistons and the broken lines 57' to 62' the other group, the pistons of the two groups being turned exactly 30° with reference to each other,—phase angle of 30° in other words. This results in that three pistons of one group (58', 60 55 and 62') are in maximum torque position with reference to the cam surfaces when the remaining pistons of the same group are in exhaust positions and all the pistons of the other group are in dead center positions.

It will be clear from Fig. 8, assuming the valve ports of the valve for both groups of pistons are as shown diagrammatically on this figure, that the rotor will turn in a clockwise direction, the pistons 58', 60' and 62' continuing to turn the 70 rotor until the cylinder ports of the pistons 58, 59 and 60 are aligned with the respective inlet ports 30'. The operation just described is the same notwithstanding whether all twelve pistons are in one plane or separated into groups say of 75

three or of six pistons each in different planes along the rotor axis.

Referring to Figs. 9 and 10, these illustrate the basic characteristics of a two-lobe cam arrangement embodying the principles of the present invention. Fig. 9 shows the theoretical generation of the cam surfaces, the lines 70 and 71 indicating minor and major axes of the cam and the points 72 disposed on the axis 71 equal distances from the axis 70 being the points of generation of the cam arcs 73. These arcs 73 may intersect as at 74 forming a dead center point of unstable equilibrium for the pistons in their innermost positions on opposite sides of the axis 71, or, alternatively at the region of the intersection of the arcs 73, the corners may be rounded as on arcs 74' for smoother operation of the motor.

Fig. 10 shows the preferred arrangement of ports in the pintle and an exemplary arrangement of pistons designated 75 to 80 inclusive. A four-port valve is recommended having intake ports 30' and exhaust ports 32 communicating with axial passages in the pintle as previously described. Also the port arrangement provides bridge portions at 32' between the inlet and exhaust ports. It will be seen that in the operation of a motor designed with this cam and the port arrangement and relationship thereto shown, the motor will turn in a clockwise direction, pistons 76 and 79 being in approximately maximum torque positions, pistons 77 and 80 being in exhaust positions and pistons 75 and 78 being momentarily on dead center at the juncture of the cam surfaces defined by the arcs 73.

It will be seen that in all the above described arrangements of cams, the cam surfaces may be machined with standard machine tools and, after machining, be finished on a circular grinder and the rounded portions of the cams, where the arcs 73 defining the major portions of the cam surfaces meet, may be similarly simply formed. Such simple manufacturing methods would be impossible on prior forms of cams, say elliptical cams.

It will be noticed that by virtue of my novel cam profile arrangement, whereby there are a circular series of cam lobes in the basic curves, the rotating pistons of the motor will balance each other substantially in regard to their centrifugal and tangential mass forces also. This dynamic balance is an additional feature of my novel improved hydro-motor, which is lacking in the motors of the prior art. The combined dynamic and hydrostatic balance of my motor allows a greater maximum speed and more uniform rotation, together with less fluctuation of the driving power of the motor, than it is obtainable with devices of similar nature of today. Since the upper speed ratio of my motor, when it is used in combination with a variable delivery pump, is substantially high, compared to the lower limit of the speed, I claim that due to the substantial dynamic balance of the pistons at any point of their rotating path results in a more silent and smooth transmission, when my motor is used in such a transmission. The improved combination of cams and pistons also results in reduced wall friction between the pistons and cylinders under the fluctuation of the rotary mass forces, which in this case is substantially less than in the case of unbalanced piston arrangements.

I claim:

1. In a high pressure rotary radial piston hydraulic apparatus, a casing, a barrel comprising a rigid cylindrical portion having coaxial

hub portions near the ends respectively, sets of anti-friction bearings mounted in the casing and on said hub portions respectively for supporting the barrel for rotation about its axis, said barrel having a set of circumferentially spaced radial cylinders disposed between the planes of the sets of bearings, a radial flange on said barrel in the plane of said cylinders and spaced axially of the barrel inwardly from the sets of bearings, said flange having radial guideways respectively aligned with the cylinders, plungers in said cylinders having end portions extending radially outwardly therefrom and lying in the associated guideways respectively, said plunger end portions being coextensive axially of the barrel with the flange, crosspins mounted in the said end portions of the plungers and extending parallel to the barrel axis and beyond the lateral limits of the flange, rollers on the respective ends of each crosspin and on their inner faces in substantially face to face abutting relation to the flange and associated plunger end portion, axially spaced parallel cam tracks surrounding the barrel between the planes of the bearings and having radial side walls extending radially of the flange alongside the radial faces thereof and in substantially abutting relationship thereto, said tracks engaging the plunger rollers for relatively rolling engagement therewith for effecting rotation of the barrel, and valve means in valving cooperation with said cylinders.

2. In a high pressure rotary radial piston hydraulic motor, a casing, a barrel comprising a rigid cylindrical portion having coaxial hub portions at the ends respectively, sets of anti-friction bearings mounted in the casing and on said hub portions respectively for supporting the barrel for rotation about its axis, said barrel having a set of circumferentially spaced radial cylinders disposed between the planes of the sets of bearings, a radial flange on said barrel in the plane of said cylinders and spaced axially of the barrel from the sets of bearings, said flange having flat parallel radial side walls and having radial guideways respectively aligned with the cylinders, plungers in said cylinders having end portions extending radially outwardly therefrom and lying in the associated guideways respectively, said plunger end portions being coextensive axially of the barrel with the flange and having flat lateral faces lying in the planes of the radial side walls of the flange respectively, crosspins mounted in the said end portions of the plungers and extending parallel to the barrel axis and beyond the said lateral faces, rollers on the ends of each crosspin and on their inner faces in substantially face to face abutting relation to the flat lateral faces and radial side walls of the flange and associated plunger end portion, axially spaced parallel cam tracks surrounding the barrel between the planes of the bearings and having flat radial side walls extending radially of the flange alongside the radial side walls thereof and in substantially abutting relationship thereto, said tracks engaging the plunger rollers for relatively rolling engagement therewith for effecting rotation of the barrel, and valve means in valving cooperation with said cylinders.

3. In a high pressure rotary radial piston hydraulic motor, a casing, a barrel comprising a rigid cylindrical portion having coaxial hub portions near the ends respectively, sets of anti-friction bearings mounted in the casing and on said hub portions respectively for supporting the barrel for rotation about its axis, said barrel hav-

ing an axial valve bore and a set of circumferentially spaced radial cylinders disposed between the planes of the sets of bearings and communicating at their inner ends with said valve bore, a 5 radial flange on said barrel in the plane of said cylinders and spaced axially of the barrel from the sets of bearings, said flange having flat radial side walls and having radial guideways respectively aligned with the cylinders, plungers in said 10 cylinders having end portions extending radially outwardly therefrom and lying in the associated guideways respectively, said plunger end portions being coextensive axially of the barrel with the flange, thrust means carried by the said end portions of the plungers and extending parallel to the barrel axis and beyond both lateral limits of the flange, axially spaced parallel reactance means surrounding the barrel between the planes of the bearings and having flat radial side walls 15 20 extending radially of the flange alongside the radial faces thereof and in substantially abutting relationship thereto, said reactance means engaging the thrust means contiguous to the lateral faces of the flange for effecting rotation of the barrel, the pitch diameter of said sets of bearings defining a cylindrical surface of substantially the same diameter as the cylindrical portion of the barrel, and valve means fitting in said barrel bore between the planes of the sets of 25 30 bearings and in valving cooperation with said cylinders and terminating between the planes of said bearings.

4. In a high pressure rotary radial piston hydraulic motor, a casing, a barrel comprising a 35 rigid cylindrical portion having coaxial hub portions at the ends respectively, sets of anti-friction bearings mounted in the casing and on said hub portions respectively for supporting the barrel for rotation about its axis, said barrel having 40 a set of circumferentially spaced radial cylinders disposed between the planes of the sets of bearings, a radial flange on said barrel in the plane of said cylinders and spaced axially of the barrel from the sets of bearings, said flange having flat 45 parallel radial side walls and having radial guideways respectively aligned with the cylinders, plungers in said cylinders having end portions extending radially outwardly therefrom and lying in the associated guideways respectively, said 50 plunger end portions being coextensive axially of the barrel with the flange and having flat lateral faces lying in the planes of the radial side walls of the flange respectively, each plunger end portion having a bore extending parallel to 55 the barrel axis, crosspins in said bores of the said end portions of the plungers and extending parallel to the barrel axis and beyond the said lateral faces, rollers on the ends of each crosspin and on their inner faces in substantially face to face 60 abutting relation to the flat lateral faces of the associated plunger end portions respectively and the radial side walls of the flange, sets of capillary needle rollers for mounting the crosspins in said bores respectively, said needle rollers being 65 substantially coextensive axially of the associated crosspins with the portion of the crosspin lying between the associated rollers, axially spaced parallel cam tracks surrounding the barrel between the planes of the bearings and having 70 flat radial side walls extending radially of the flange alongside the radial side walls thereof and in substantially abutting relationship thereto, said tracks engaging the plunger rollers for relatively rolling engagement therewith for effecting 75

rotation of the barrel, and valve means in valving cooperation with said cylinders.

5. In a radial piston pump or motor, a casing, a rotatable barrel, a reactance means, piston and cylinder assemblies carried by the barrel and cooperating with the reactance means, said barrel having an axial valve bore and ports operatively communicating the assemblies respectively with said valve bore, a pintle mounted in the casing and having a valve portion extending 10 into the axial bore of the barrel and fitting said axial valve bore, said pintle valve portion having a plurality of circumferentially spaced high pressure fluid ports and low pressure fluid ports successively communicable with the ports of said 15 assemblies as the barrel rotates, a plurality of circumferentially spaced ducts extending within and longitudinally of the pintle and connected respectively to different ports of one group of said pintle ports and each being radially spaced 20 throughout its length from the pintle axis, and a single duct of larger cross sectional area than said spaced ducts extending substantially axially within said pintle and being connected to all of the ports of the other group of pintle ports and 25 extending alongside the first mentioned ducts.

6. In a high pressure, rotary, radial piston hydraulic motor, a barrel comprising a rigid cylindrical portion having circumferentially spaced radial cylinders therein, valve means for the 30 cylinders, anti-friction bearing means at opposite sides of the plane of the cylinders and supporting the barrel for rotation about its axis, a radial flange on said cylindrical portion in the plane of the cylinders, and having radial guideways respectively aligned with the cylinders, plungers in the cylinders, each plunger having a portion reciprocable in and guided by an associated guideway and substantially coextensive axially of the barrel with the flange, crosspins 40 anti-frictionally mounted in the said portions of the plungers and extending parallel to the barrel axis beyond the lateral limits of the flange, rollers on the respective ends of each crosspin and having their inner faces in substantially face to face abutting relation respectively to the lateral faces of said portions, axially spaced parallel reactance means surrounding the barrel and having side walls extending radially of the flange alongside the radial faces thereof and in substantially abutting relationship thereto, said reactance means 50 engaging the plunger rollers substantially contiguous to the lateral faces of the flange for relative rolling cooperation therewith for effecting rotation of the barrel.

7. In a high pressure, rotary, radial piston hydraulic motor, a barrel comprising a rigid cylindrical portion having circumferentially spaced radial cylinders therein, valve means for the cylinders, anti-friction bearing means at opposite sides of the plane of the cylinders and supporting the barrel for rotation about its axis, a radial flange on said cylindrical portion in the plane of the cylinders, and having radial guideways respectively aligned with the cylinders, plungers in the cylinders, each plunger having a portion reciprocable in and guided by an associated guideway and substantially coextensive axially of the barrel with the flange, crosspin means mounted in said portions of the plungers and extending 60 parallel to the barrel axis beyond the lateral limits of the flange, sets of capillary needle rollers for rotatably mounting the crosspin means in the associated portions, said needle rollers being substantially coextensive axially with the associated 65

plunger portions, axially spaced parallel reactance means surrounding the barrel and having side walls extending radially of the flange alongside and in substantially abutting relation to the 5 radial faces thereof, and said reactance means operatively engaging the extending portions of the

crosspin means substantially contiguous to the lateral faces of the flange for relative rolling cooperation with said extending portions for effecting rotation of the barrel.
